(57) **CLAIM**

The ornamental design for a lollipop, as shown and described.

DESCRIPTION

FIG. 1 is a perspective view of my new lollipop design;
FIG. 2 is a front view of my new lollipop design, which is the
same as the rear view;

FIG. 3 is a left side view of my new lollipop design, which is
the same as a right side view;

FIG. 4 is a top view of my new lollipop design; and,

FIG. 5 is a bottom view of my new lollipop design.

The broken lines shown in the drawings represent environmental
structure and form no part of the claimed design.
